UNITED STATES PATENT OFFICE.

SAMUEL R. SARGENT, OF CLEVELAND, OHIO.

DESIGN FOR A WASHBOARD.

SPECIFICATION forming part of Design No. 33,805, dated December 25, 1900.

Application filed October 24, 1900. Serial No. 34,215. Term of patent 14 years.

To all whom it may concern:

Be it known that I, SAMUEL R. SARGENT, a citizen of the United States, residing at Cleveland, in the county of Cuyahoga and State of Ohio, have invented and produced a new and original Design for Washboards, of which the following is a specification.

In the accompanying sheet of drawing the single perspective view illustrated shows my new and original design as I make it, and the leading or material feature of said design consists especially in a washboard in which the back of the board has the appearance as shown.

In said view as thus illustrated the essential feature of the design is found in the back

surface of the washboard, comprising surfaces A, B, and C, the otherwise plain surface A being relieved by a number of conspicuous spots *a*, scattered over and decorating said surface, while plain surface C, above surface A, is relieved by a circular ornamentation *c* at its middle.

What I claim is—

The design for a washboard, substantially as herein shown and described.

Witness my hand to the foregoing specification this 17th day of October, 1900.

SAMUEL R. SARGENT.

Witnesses:

M. A. SHEEHAN,
R. B. MOSER.
